TYPEWRITING MACHINE

Henry Allen Avery, Groton, N. Y., assignor to
L. C. Smith & Corona Typewriters Inc., Syra-
cuse, N. Y., a corporation of New York

Application August 18, 1933, Serial No. 685,693

3 Claims. (Cl. 197—74)

This invention relates to improvements in type-writing machines and more particularly to type-writing machines in which the type bars are given a shifting movement for case changing.

The invention has for its principal objects to provide a simple, efficient and compact typewriting machine in which the case shifting movement is imparted to the type bars; to provide simple and efficient means for supporting, guiding and imparting case shift movement to the type bars of a typewriting machine; and to provide a simple and compact case shift mechanism for a small and low portable typewriting machine of the kind having a shiftable type bar segment supporting the type bars to strike upon the upper front quarter of the platen.

To the foregoing and other ends which will hereinafter appear, the invention consists in the features of construction, arrangements of parts, and combinations of devices set forth in the following description and particularly pointed out in the appended claims.

In the accompanying drawings illustrating the preferred embodiment of the invention:

Fig. 1 is a vertical central longitudinal sectional view of the improved typewriting machine;

Fig. 2 is a view similar to Fig. 1 but showing the type bar segment and type bars shifted into position for typing upper case characters; and

Fig. 3 is a fragmentary front view of the machine as viewed perpendicularly to the plane of the type bar segment, the parts of the case shift mechanism being in normal lower case position as in Fig. 1.

The stationary main frame of the machine is formed of sheet metal and comprises side plates 10, a front end plate 11, a rear end plate 12, a rearwardly tilted cross plate 13 held to and extending between the side plates in the rear half of the frame, and a platen carriage supporting bed plate 14. Bed plate 14 has upwardly and rearwardly extending raceway flanges 15, is tilted rearwardly and downwardly to lie in a plane perpendicular to that in which lies the cross plate 13, preferably has its forward edge lying substantially in the plane of plate 13, is seated on lugs 16 which extend inward from the top edges of the side plates, and is also seated on lugs 17 which extend rearwardly from the top edge of the cross plate 13. Screws 18 hold the bed plate to lugs 16, and screws 19 hold the bed plate to lugs 17.

The platen 20 is journaled in the end members of the rearwardly and downwardly tilted platen carriage 21, and the base of the carriage has forwardly and downwardly extending race-

way flanges 22 between which and the raceway flanges 15 on the bed plate ball bearings 23 are confined.

The type action may be varied as to construction, that shown being of the kind disclosed in my co-pending application Serial No. 586,319, filed January 13, 1932, and need be only briefly described. The type bars 24 are pivoted on the pivot wire 25 in the slotted type bar segment 26 which lies parallel to the cross plate, the pivot wire lying in a plane tangent to the platen at the upper front portion of the platen as is usual in three-quarter or semi-front strike typewriting machines. Draw links 27 extend upwardly and forwardly from the heels of the type bars to the upper ends of upstanding levers 28 which are pivoted on an arcuate pivot wire 29 in the horizontally arranged slotted segment 30. Segment 30 curves rearward from the middle to the sides of the machine and is held at its ends to the side plates of the frame. Levers 28 are actuated by the type keys 31 connected by stems 32 to toggle devices 33. Each toggle device is pivotally anchored to two pivot wires 34 and 35 held in a support 36 attached to the side members of the frame, and the toggle devices are also pivotally anchored at 37 to the levers 28. A return spring 38 for each type action is anchored at its ends to the toggle device and upstanding lever of the type action. The key carrying stems are normally engaged under a stop device 39 extending across the frame and held to the sides of the frame.

The type bar segment 26 has three bosses 40 extending rearward therefrom at its middle and end portions to the front face of a shiftable supporting plate or shift frame member 41 to which the segment is held by screws 42 which are threaded into said bosses. Plate 41 lies parallel to frame plate 13 closely in front of said plate 13.

At each of the two upper corners thereof plate 41 is provided with a forwardly bent lug 43 having a closed slot 44 extending parallel to the plane of plate 41 to form a short raceway member or flange on plate 41. Each lug 43 abuts the outer edges of a pair of superposed bracing lugs 45 and 46 formed on plate 41 and lying flatwise in planes extending forward and upward perpendicular to the plate. Small plates 47, held flatwise to the front face of plate 13 outside of raceway members 43 by screws 48, each have a short forwardly bent lug 49 provided with a closed slot 50 extending parallel to the plane of plates 13 and 47 to form fixed raceway members opposed to the raceway members 43 of the shift frame. In each of the

races thus formed adjacent the two sides of the machine there is confined a single ball bearing 51. Each raceway member 49 abuts the inner ends of two superposed bracing lugs 52 and 53 5 extending forward and upward flatwise from plate 47.

A pair of forwardly and upwardly extending sheet metal arms 54, fastened at 55 to lugs 45, have an arcuate type bar rest 56 secured at its 10 ends at 57 to the forward ends of said arms, said rest engaging under the type bars to support the arcuate system of type bars in an upwardly and forwardly inclined position for action to the platen by the type keys.

15 The main plate member 41 of the shift frame has a lug 58 extending flatwise rearwardly and downwardly from the lower edge of said plate midway the ends of the plate and lying in a plane perpendicular to the plate. The cross plate 13 20 of the main frame is cut out at 59 to afford clearance for up and down movement of lug 58 with plate 41. Threaded up through the rear part of lug 58 is an adjustable shift stop screw 60 normally engaged under a rearwardly and downwardly inclined and slightly springy shift stop lug 61 on a stop-carrying plate 62 held by screws 63 to plate 13. Plate 62 has a lug 64 extending flatwise forward and upward through the cut out 25 59 in plate 13, and a slightly springy sheet metal bar 65 lies flatwise against the bottom face of lug 64 and is held at one end to said lug by screws 79 and 80, one of which may have a lock nut thereon as shown. Near its free end bar 65 has threaded upward therethrough an adjustable 30 shift stop screw 66 which passes loosely through a suitable clearance aperture in lug 64 and has its upper end spaced below, but lying in the path of movement of the forward end of lug 58 on the shift frame plate 41 to arrest downward movement of the shift frame and the bar segment.

40 At its two lower corners the main plate member 41 of the shift frame is provided with forwardly and downwardly extending lugs 67 lying flatwise in vertical fore and aft planes. A rock shaft 45 68 extends across the main frame and is journaled at its ends in the side plates 10 of the main frame. This rock shaft extends above segment 30 and under the type bars 24 and draw links 27 intermediate the ends of the type bars, 50 and has a downwardly bowed middle section to afford clearance for the draw links for the type bars in the middle section of the type segment. Rearwardly and downwardly extending rock arms 70 55 on the higher end sections of the bowed rock shaft, adjacent the outer ends of the middle downwardly bowed section of the shaft, are connected by transversely extending horizontal pivots 69 to the forward ends of lugs 67 and serve as lower supports and guides for the shift frame.

60 A plane parallel to the planes of the type bar pivot wire, segment 26, and plates 41 and 13, passes through the axes of the ball bearings 51 and pivots 69 in both the upper and lower case 65 positions of the shift frame, the pivots 69 moving, in shifting from lower case to upper case position, between points equal distances above and below a plane which is perpendicular to the above mentioned planes and passes through the axis of the rock shaft, thus providing for printing of 70 both lower and upper case types on their feet. In passing from one case position to the other the shift frame rocks slightly upon the ball bearings 51 and pivots 69. The draw links 27 swing about their pivotal connections with levers 28 during 75 case changing movements, their rear ends moving

between points equal distances above and below planes intersecting said connections and perpendicular to the plane of plate 13.

Bellcranks 71 are fixed on rock shaft 68 adjacent the ends of the shaft, each bellcrank having a forwardly extending arm and an upwardly extending arm. Springs 72 are attached at their forward ends to brackets 72 held to side plates 10 of the frame, said springs being attached at their rear ends to the upper ends of the upwardly extending arms of bellcranks 71 to normally hold the shift frame and type basket shifted upward into lower case printing position, the lower case types being nearest the type bar pivots in the machine shown and as is common in typewriting machines.

15 Bellcranks 71 are rocked against the pull of springs 72, to shift the shift frame downward to the upper case printing position shown in Fig. 2, by means of either one of two shift key levers 74 20 located adjacent opposite sides of the main frame. Each shift key lever 74 extends fore and aft of the machine and is fulcrumed between its ends on a horizontally and transversely extending pivot 75 carried by the main frame. The forwardly extending arm of each shift key lever carries a shift key 76. A short slot 77 extends forward from the rear end of each shift key lever, providing a forked lever end embracing a horizontally and transversely extending stud 78 carried by the forwardly extending arm of the adjacent bellcrank 71. Springs 72 also serve to return the shift key levers to normal position.

25 A segment shift mechanism is thus provided which operates easily, rapidly and quietly, and which is also of simple, light and compact construction.

30 What I claim is:

1. A typewriting machine having a main frame, a type basket supporting shift frame, means on 40 said frames forming two up and down extending ball races spaced apart transversely of the machine, a single bearing ball in each ball race for supporting the shift frame for sliding and pivotal movement, a rock shaft journaled on the 45 main frame and extending transversely of the machine, a pair of parallel rearwardly extending rock arms on said shaft, horizontal transversely extending pivots connecting the rear ends of said rock arms to the shift frame at a level below the ball races, cooperating stop means on the main and shift frames for limiting up and down movements of the shift frame, a bellcrank fixed on 50 said rock shaft having a forwardly extending arm and an upwardly extending arm, a spring connected to said upwardly extending arm of the bellcrank and to the main frame for rocking the shaft in one direction, a key lever fulcrumed on the main frame having a rearwardly extending arm provided with a longitudinal slot and also 55 having a forwardly extending arm, a shift key carried by the forwardly extending arm of the key lever, and a horizontal transversely extending stud carried by the forwardly extending arm of the bellcrank and engaged in the slot in the rearwardly extending arm of the key lever.

60 2. In a typewriting machine, the combination of a main frame, a platen carriage mounted on the main frame, a roller platen on the carriage, a type bar pivot segment, type bars pivoted in said segment and having heels, a shift frame supporting said segment with the segment lying in an upwardly and rearwardly inclined plane, a type bar rest carried by the shift frame and supporting the type bars to normally extend upward. 65 70 75

- ly and forwardly from their pivots, key operated draw links for actuating the type bars and normally extending upwardly and forwardly from the type bar heels, means on the main frame and 5 shift frame forming a pair of transversely spaced ball races extending in an upwardly and rearwardly inclined plane, a single bearing ball in each race, said balls supporting the shift frame for sliding and pivotal movement, a shift key 10 operated rock shaft extending transversely of the main frame and having horizontal end portions journalled in the frame and a downwardly bowed middle portion affording clearance for the actuating draw links for the central type bars, a pair of 15 parallel rock arms fixed on said end portions of said shaft and extending downwardly and rearwardly therefrom and pivotally connected at their rear ends to the shift frame at a level below the ball races, and cooperating stop means on the 20 main and shift frames for arresting shifting movement of the shift frame in lower and upper case printing positions in both of which the type bar pivots are located in the same upwardly and rearwardly inclined plane tangent to the platen at 25 a printing point on the upper front quarter of the platen.
3. In a typewriting machine, the combination of a main frame, a type basket supporting shift frame, means on said frames forming two opposed ball races spaced apart transversely of the machine, a single bearing ball in each ball race for supporting the shift frame for sliding and pivotal movement, a rock shaft journalled on the main frame and extending transversely of the machine, a pair of parallel rock arms fixedly held to said shaft and spaced apart transversely of the machine, horizontally aligned pivots extending transversely of the machine and pivotally connecting the rock arms to the shift frame at points spaced from the ball races lengthwise of the races, cooperating stop means on the main and shift frames for limiting case shift movements of the shift frame, a bellcrank fixedly held to the rock shaft, a spring connected to the main frame and one arm of the bellcrank to rock the shaft in one direction, and a shift key lever fulcrumed on 20 the frame and having a key carrying arm and an arm having a pin and slot connection with the other arm of the bellcrank to rock the shaft in opposition to said spring. 25

HENRY ALLEN AVERY.
